UNITED STATES PATENT OFFICE.

JOSEPH MORICCA AND FRED MORICCA, OF WELLSVILLE, NEW YORK.

SNOWPLOW.

Application filed August 24, 1921. Serial No. 495,070.

To all whom it may concern:

Be it known that JOSEPH MORICCA and FRED MORICCA, the former a citizen of the United States and the latter a citizen of 5 Italy, residing at Wellsville, in the county of Allegany and State of New York, have invented a certain new and useful Improvement in Snowplows, of which the following is a specification.

10 This invention relates to improvements in what may be termed, generally, snow plows, more especially means or appliances for locomotives for cleaning the tracks or rails of railways.

15 This invention has for its object to provide for clearing or cleaning the railway tracks or rails especially in case of light falls of snow, in a simple, expedient, effective and inexpensive manner.

20 A further object of the invention is to provide for the portability of the device in applying it for use particularly to the locomotive or when not required for use.

Other objects of the invention, together 25 with the foregoing, will be apparent from the following description of the construction and operation of the invention.

The invention therefore consists of certain instrumentalities and features of construction substantially as hereinafter more 30 fully disclosed and pointed out by the appended claims.

The accompanying drawing illustrates the preferred embodiment or one form of 35 my invention, wherein it will be understood that various changes and modifications as relate to the detailed construction and arrangement of parts may be made without departing from the spirit or scope 40 of the claims, in which drawing:—

Figure 1 is a side elevation of my invention, showing it as applied to the cow-catcher of a locomotive, the latter being disclosed only fragmentarily.

45 Figure 2 is a detached front view of my invention, with the attaching nut-equipped bolts thereof.

Figure 3 is a horizontal section taken through Figure 2 on the line 3—3.

50 Figure 4 is a vertical section taken on the line 4—4 of Figure 1.

In carrying out my invention, I provide a suitable support 1 preferably of general V-shape to adapt it to be conveniently ap-

plied to a locomotive-cow-catcher, or otherwise for use. The support 1 is preferably formed of an upper metallic member 2 also conforming to the above indicated shape and having suitably bolted or screwed to its inner surface preferably duplicate pieces 60 or blocks of rubber 3, the member 2 having secured rigidly or integrally therewith a downwardly extending plate 3^a which forms in combination with the outer vertically disposed portion 2 a rectangular channel 65 adapted to embrace said rubber blocks or pieces. The rubber blocks or pieces 3 have bolted or clamped therebetween preferably steel strips 4, or other flexible medium, adapted to extend about a couple of inches 70 below the tops or treads of the rails and clear away snow laterally therefrom, the lower edges of the rubber blocks or pieces 3 which are inclined laterally or obliquely to render them freely yieldable, engaging and 75 clearing the snow off the rail tops, thus providing for readily and effectually removing all snow, which would otherwise accumulate upon the rails or track, therefrom. The metallic member 2 of the support 1 has 80 passed or extended through orifices 5 therein in threaded bolts or rods 6 whose lower ends are suitably held to the bottom rail of the cow-catcher and provided with jam nuts 7 above the member 2, adapted to engage said 85 member, whereby the snow cleaner as above described is adapted to be elevated when not required for service and so as to be out of the way of the cow-catcher, and yet remain portably attached thereto so as to be 90 readily brought into service when conditions require.

In rear of the aforesaid cleaner or arrangement of parts, and also arranged at the sides of and under the platform or support of the cow-catcher, are additional cleaners 8 of substantially like constituent parts, the metallic members being designated as 9, the rubber blocks as 10, the steel brushes or flexible members as 11 and the elevating threaded bolts or rods as 12, the jam nut answering to the jam nuts applied to the foresaid jam nut being designated as 13. The parts or cleaners are adapted to occupy an angular position or relation to 105 the rails as to clear snow away therefrom and ride above any otherwise obstructing railway-ties at a point between the rails.

We claim and desire to secure by Letters-Patent:—

1. A device of the type described comprising a cleaner for railway tracks, having an upper member formed with a downwardly opened channel, a pair of elastic members in and projecting below said channel, and flexible members in said channel and between said elastic members, and projecting below said elastic members and into proximity with the track.

2. A device of the type described, comprising the combination of a support conforming to the cow-catcher and having

spaced downwardly extending portions, of 15 downwardly projecting elastic members within said portions, of flexible members disposed between said elastic members, and of a bolt for securing all of said members and support together.

In testimony whereof, we affix our signatures, in the presence of two witnesses.

JOSEPH MORICCA.
FRED MORICCA.
